H. L. PETERSON.
COMBINED SECRET POCKET AND HOSE SUPPORTER.
APPLICATION FILED MAY 16, 1917.

1,313,229.

Patented Aug. 12, 1919.

UNITED STATES PATENT OFFICE.

HARRIETT LUCINDA PETERSON, OF PORTLAND, OREGON.

COMBINED SECRET POCKET AND HOSE-SUPPORTER.

1,313,229.

Specification of Letters Patent. Patented Aug. 12, 1919.

Application filed May 16, 1917. Serial No. 169,122.

To all whom it may concern:

Be it known that I, HARRIETT LUCINDA PETERSON, a citizen of the Dominion of Canada, and a resident of Portland, county of 5 Multnomah, State of Oregon, have invented a certain new and useful Improvement in Combined Secret Pocket and Hose-Supporter, of which the following is a specification.

10 The object of my invention is to provide a secret pocket and means for supporting the same on the leg of the wearer, which means shall also serve as a hose supporter, being suspended from a supporting element; thus, 15 if worn by a woman, being then supported by being attached to the corset.

It is further my object to provide for the comfort of the wearer by having the pocket bear snugly but easily on the thigh of the 20 leg; also to insure ample flexibility in the attachments by which it is supported, so as to permit free movement of the leg, without causing undue strain on such attachments. Also to provide for safety by so suspending the purse that in case of the suspending means giving way in part, the 25 pocket will still be held in upright position, and so avoiding the contents of the purse being spilled out.

30 The details of construction and arrangement of the parts are more readily understood by having reference to the accompanying drawings, in which:

Figure 1 represents a front elevation of 35 my device as worn, my device being shown as supported from the corset; and

Fig. 2 is a rear face elevation of my device by itself.

a represents the lower portion of the cor- 40 set and b the hose. My device comprises parallel elastic bands c, c' the lower ends of which are adjustably fastened by clasps d to a bail or hanger bar e. The latter is of loop-like elongated form comprising upper 45 and lower members, f, g. The upper member comprises bars h, h', horizontally aligned and spaced apart by angular portions or abutments i. The lower member has a bow- 50 shape form the middle portion, j, of which is adapted to constitute a bar the ends of which are formed with angular abutments k, k. The purpose of the bars h, h' of the upper member and the angular abutments

i thereof, as apparent, is not only to provide means for attaching the lower ends of the 55 elastic bands c, c', but also hold such lower ends against lateral movement. The purpose of the bar j of the lower member g and its angular abutments k is to provide means to which to fasten the strap m of the hose 60 clamp n, the hose clamp being of the conventional construction, as apparent.

The pocket o has a flap p, and fastening means q for the flap, preferably a snap, such as used on gloves. The upper part of the 65 pocket has an elastic band sewed crosswise on it, as indicated by r, so as to hold the mouth of the pocket shut, even though the flap p be unfastened. The pocket o is fastened at its upper parts, at at s, s', by stitches 70 to the elastic bands c, c'. At the sides, near the bottom portion of the pocket o, are provided transverse loops as t, t', which encompass the elastic bands c, c', the loops t, t' holding the lower portion of the purse in place on the 75 bands c, c'; that is to say, holding the purse from swinging outward from said elastic bands and from moving crosswise thereof.

The pocket is made of flexible material 80 so as to rest comfortably on the leg. The hose supporter, to which the pocket is attached, is permanently secured to the bottom of the corset, so that it may not become accidentally detached, as would be the case where secured by some such means as a fastening clamp. The pocket is secured at its 85 upper corners to prevent the same from doubling over, or being drawn into an uncomfortable position, as would be the case where the pocket is suspended at the central top portion only and carrying articles of 90 some weight.

The front of the pocket is made gathered 95 so as to have a fullness as at u, permitting expansion and providing ample capacity.

Should either of the elastic bands c, c' wear away at the top or bottom, the remaining band would still serve to hold the pocket upright by that one of the loops t, t' circling the remaining band.

I claim:

An article of the character described comprising two pendent parallel elastic bands adapted for attaching to a supporting element fastened on the person, a hanger bar of 105 elongated form comprising upper and lower

members the ends of the upper members including horizontally alined portions to which the lower ends of said bands are attached, means adapted to hold said lower ends against lateral movement on said upper member, a hose-securing device attached at the middle of the lower member of said

hanger bar, a purse, stitches fastening the upper end thereof to each of said elastic bands, and transverse loops spaced apart on the lower part of the back of the pocket, such loops encompassing said bands respectively. 10

HARRIETT LUCINDA PETERSON.
